UNITED STATES PATENT OFFICE.

WILLIAM H. SAUVAGE, OF NEW YORK, N. Y., ASSIGNOR, BY MESNE ASSIGNMENTS, TO THE GOULD COUPLER COMPANY, A CORPORATION OF MARYLAND.

SLACK ADJUSTER.

Application filed May 17, 1924. Serial No. 714,169.

This invention relates to improvements in slack adjusters and more particularly to automatic slack adjusters particularly adapted for use with a foundation brake 5 rigging of railway vehicles.

One of the objects of the present invention is to provide a simple and practical automatic slack adjuster of the above general character adapted to be actuated on excess piston travel for the purpose of permanently taking up and holding the excess travel of the brake rigging.

A further object of the invention is to provide a slack adjuster of the above general character adapted to positively insure uniform piston travel at each application of the brakes.

A further object is to provide a simple and practical mechanism which may be inexpensively manufactured, assembled and installed on brake rigging now in general use without material modification of the existing parts.

Other objects will be in part obvious from the annexed drawings and in part indicated in connection therewith by the following analysis of the invention.

This invention accordingly consists in the features of construction, combination of parts and in the unique relation of the members and in the relative proportioning and dispositioning thereof, all as more completely outlined herein.

To enable others skilled in the art so fully to comprehend the underlying features thereof that they may embody the same by the numerous modifications in structure and relation contemplated by this invention, drawings depicting a preferred form have been annexed as part of this disclosure, and in such drawings like characters of reference denote corresponding parts throughout all the views, in which—

Figure 1 is a side elevational view partly in section of such parts of the foundation brake rigging and adjuster as are necessary to fully understand the same;

Figure 2 is a plan view thereof; and

Figure 3 is a detail sectional view.

As is well known to those familiar with the art, air brake systems now in general use on railway cars employ a main cylinder, the piston of which is adapted to be connected with a live lever and a dead lever is pivotally connected at one of its ends to the

rear of the brake cylinder, the two levers being connected by means of a tie rod whereby as the piston moves outwardly on application of the brakes the brakes will be applied. It is to this general type of mechanism that the invention hereinafter described is adapted to be applied; that is, a brake cylinder indicated at 5 is provided with the usual piston 6, and piston rod 7; the end of which is adapted to be connected with a live lever (not shown). At the rear of this cylinder 5 is mounted a dead lever 8 which, in the present case, has its pivot point 10 supported on a movable adjusting rod 11 carried by a suitable frame 12 as shown. This rod 11 passes through a housing or chamber 13 formed by the sides of members 12 and stop lugs 14 within which are a plurality of permanent take-up and holding dogs 15 held in canted position by means of a spring 16, Figure 2. The rod 11 also continues through a second housing 17 movable within the frame 12 and in which is mounted one or more dogs 18 also held in canted position by means of a spring 20. This second housing 17 is provided with a tubular extension 21 terminating in a piston 22 having a limited range of movement of about half an inch. This limit may be enforced by the construction shown in Figure 3 or by the lugs 26 in Figure 1 or both if desired.

This piston is actuated by air pressure admitted through pipe 23 extending to a port 24 in the side wall of the cylinder 5 when the piston 6 exceeds its predetermined piston travel. In other words, the port 24 is located six or seven inches from the right end wall, according to the standard piston travel, and when this piston travel is exceeded due to wear of the brake shoes or associated parts of the rigging then the compressed air passes through the pipe 23, acts on the piston 22 and moves the temporary take up and holding means, including the housing 17, relatively along the rod 11 a distance equal to the travel of the piston 22, and thereby compresses a spring 25. On release of the brakes this spring 25 expands to move the piston back and with it the chamber 17 with its associated parts to normal position. The dogs 18 in the position as shown will effectively engage the rod 11 and move the same relatively towards the right with respect to the permanent take

up and holding dogs 15, thereby correspondingly shifting the pivot point 10 of the dead lever 8. In this manner the excess travel is permanently taken up and held.

5 It will thus be seen that this mechanism ensures a substantially uniform piston travel of the brake rigging at all times, for as soon as excessive piston travel occurs the mechanism is actuated to take up the slack and 10 prevent any further excess movement until the parts have worn to an extent to justify the same. The degree of take up at each operation, of course, can be controlled to a 15 large extent by the limit of movement of the piston 22, as shown in detail in Figure 3.

The invention is of simple and practical construction applicable to brake rigging now in general use without material modification, as it may be easily attached to the 20 standard brake cylinder, and is well adapted to accomplish among others all of the objects and advantages herein set forth.

Without further analysis, the foregoing will so fully reveal the gist of this invention 25 that others can by applying current knowledge readily adapt it for various applications without omitting certain features that, from the standpoint of the prior art, fairly constitute essential characteristics 30 of the generic or specific aspects of the invention, and, therefore, such adaptations are and should be intended to be comprehended within the meaning and range of equivalency of the following claims.

35 I claim:—

1. In an automatic slack adjuster mechanism, in combination, a power cylinder having a piston with a predetermined piston travel for brake application, a dead lever, a 40 movable fulcrum therefor, and means actuated on excess travel of the piston for moving said movable fulcrum on release of the brakes, said means including an adjusting rod connected with the dead lever, relatively movable permanent and temporary 45 take-up holding means co-acting with said rod, one of which is moved on excess travel during the application of the brakes and the other of which is actuated on release of the brakes, the temporary take-up means being freely movable with respect to the adjusting rod during excess travel of the piston.

2. In an automatic slack adjuster mechanism, in combination, a power cylinder having a piston with a predetermined piston travel for brake manipulation, a dead lever, a movable fulcrum therefor, and means actuated on excess travel of the piston for moving said movable fulcrum on release of the brakes, said means including an adjusting rod connected with the dead lever, relatively movable permanent and temporary take up and holding means co-acting with said rod, one of which is freely movable with respect to said rod on excess travel

during the application of the brakes and the other of which is actuated on release of the brakes, and a second piston having a limited range of travel adapted to be actuated on excess travel of the main power 70 piston for actuating said mechanism.

3. In an automatic slack adjuster mechanism, in combination, a power cylinder having a piston therein, a support at the rear end of said cylinder, an adjusting rod carried thereby, a dead lever having a connection with said adjusting rod, means for preventing movement of the adjusting rod during the application of the brakes, said means comprising a plurality of permanent holding dogs mounted in said support, and means for moving said adjusting rod relative to the first means on release of the brakes if excess travel of the power piston takes place, said means including an auxiliary piston adapted 80 to be actuated by air pressure from the power cylinder when the main piston exceeds its normal path of travel.

4. In an automatic slack adjuster mechanism, in combination, a power cylinder having a supporting frame at one end thereof carrying an adjusting rod, a lever pivotally connected with said adjusting rod, a plurality of permanent take-up and holding dogs co-acting with said adjusting rod, a temporary holding dog mounted in a movable housing within said frame and co-acting with said adjusting rod, said holding dog adapted to be moved on excess travel of the power piston to temporarily take up the excess travel and move said adjusting rod relative to the permanent take up and holding means on release of the brakes.

5. In an automatic slack adjuster mechanism, in combination, a power cylinder having a piston therein with a predetermined piston travel for brake application, a supporting frame at one end thereof carrying an adjusting rod, a lever pivotally connected with said adjusting rod, a plurality of permanent take-up and holding dogs mounted in a housing within said frame and co-acting with said adjusting rod to prevent movement thereof during application of the brakes, a temporary holding dog mounted in a second housing movable within said frame, and means including an auxiliary piston at one end of said second housing for moving said adjusting rod relative to said permanent holding dogs upon release of the brakes 115 when excess travel of the main power piston takes place.

6. In an automatic slack adjuster mechanism, in combination, a power cylinder having a piston with a predetermined piston travel for brake application, a frame at the rear end of said cylinder, an adjusting rod carried thereby, a dead lever having a movable connection with said adjusting rod within said frame, a housing formed in said

frame, a second housing positioned within said frame and movable relative thereto, said second housing having an auxiliary piston at one end thereof adapted to be actuated by air pressure from the main power cylinder when the main piston exceeds its normal path of travel, relatively movable permanent and temporary take-up and holding means positioned in said housings and coacting with said adjusting rod, one of said means being freely movable with respect to said rod during excess piston travel, and the other of said means being actuated upon release of the brakes, and a spring acting between said auxiliary piston and said frame 15 adapted to restore the parts to normal position upon release of the brakes after excess travel thereof has occurred.

In witness whereof I have hereunto signed my name.

WILLIAM H. SAUVAGE.
